CLAIM

The ornamental design for a wine rack, as shown and described.

DESCRIPTION

FIG. 1 is a perspective view of the wine rack;
FIG. 2 is a front view thereof;
FIG. 3 is a rear view thereof;
FIG. 4 is front view of the wine rack shown removed for clarity of disclosure;
FIG. 5 is rear view thereof;
FIG. 6 is a first side view thereof; and,
FIG. 7 is a second side view thereof.
Any details shown in broken lines form no part of the claimed design.
